[57] CLAIM

The ornamental design for a stackable in-line bulk food display, as shown and described.

DESCRIPTION

FIG. 1 is a perspective view of a stackable in-line bulk food display showing our new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a perspective view of a single shelf unit shown separately for clarity of disclosure only;

FIG. 8 is a front elevational view thereof;

FIG. 9 is a rear elevational view thereof;

FIG. 10 is a left side elevational view thereof;

FIG. 11 is a top plan view thereof; and,

FIG. 12 is a bottom plan view thereof.

The curved oblique line shading above the single shelf units represents a reflective surface.
